UNITED STATES PATENT OFFICE.

HARVEY MULLENDORE, OF FORT WAYNE, INDIANA, ASSIGNOR TO PERFECTION BISCUIT COMPANY, OF FORT WAYNE, INDIANA, A CORPORATION.

PACKAGING MACHINE.

Application filed June 1, 1926. Serial No. 112,764.

The invention relates to machines for packaging articles and it is especially directed to machines designed to package crackers, cakes, cookies and other articles of food as well as many other articles or commodities.

The object of the invention is to provide a novel machine by which to automatically insert various articles into containers, 10 economically and efficiently. Other objects and advantages will appear hereinafter.

The invention consists of an endless series of movable receptacles for the articles, 15 means to convey the empty containers to the machine, means to move the containers successively into and out of register with a receptacle, means to eject the articles from the receptacle into the container, and means to convey the filled containers from the machine.

An embodiment of the invention is illustrated in the accompanying drawings in which Figure 1 is a plan view of a machine embodying the invention; Fig. 2 a side elevational view of the same; Fig. 3 an end elevational view of the same; Fig. 4 a cross-sectional view on line 4-4 of Fig. 1; Fig. 5 a plan view of a fraction of the ejector pusher; Fig. 6 an end view of the devices shown in Fig. 5; Fig. 7 a side elevational view of the lower flap opener; Fig. 8 a rear elevational view of the said opener; Fig. 9 a side elevational view of the container support and latch; Fig. 10 a plan view of the same; Fig. 11 a side view of the actuating member of the upper flap opening member, and Fig. 12 a detail view of the reduction gears driven by the main shaft.

In the illustrative embodiment of the invention, 1 is the main frame of the machine formed of side members 2 and cross members 3 suitably tied or formed together. The mechanism is entirely supported on this frame so that the machine may be portable or fixed.

Preferably the machine is driven by an electric motor 4 suitably mounted on the main frame. A belt 5 is engaged on the pulley 6 secured to the motor shaft, and the belt is also engaged on the pulley 7, of suitable ratio, loosely mounted on the main shaft 8.

A gear 9 (Figs. 1, 3 and 12) is secured

to or integral with the pulley 7 and meshes with a gear 10 loosely mounted on a spindle 11. A pinion 10^a, integral with or secured to the gear 10, meshes with a gear 12 secured to the shaft 13. The ratio of the said train of gears is predetermined so as to cause the pulley 7 to drive the shaft 13 at a selected speed. A sprocket chain 14 engages a sprocket 13^a secured to the shaft 13 and a sprocket secured to the shaft 8 for driving said shaft 8 at the selected speed.

A sprocket 8^a on the shaft 8 drives, by means of the chain 15, a sprocket 16 secured to the shaft 17. This shaft 17 projects laterally from the main frame and its outer end is borne by the bearing 18 formed on the frame member 19. A pulley 20 is secured to the shaft 17, and an endless belt 21 is mounted upon the pulley and upon an idler pulley 22 adjustably mounted on the frame 23 mounted on the front side of the main frame. This belt, by the rotation of the shaft 17, is caused to travel in the direction of the arrow (Fig. 1) and carries the empty cartons or containers to the elevating mechanism about to be described. The empty cartons or containers are deposited upon the belt in any suitable manner, as by hand. In Fig. 4, I illustrate a rectangular carton C, such being in common use for the storage of crackers, cookies and various other commodities.

Below the conveyer belt 21 and between it and the main frame 1 is another conveyer belt 24 that is supported similarly to the belt 21 and is driven by a pulley 25 secured to a countershaft 26 supported on the main frame and the frame member 19. A crossed belt 27 is engaged on a pulley 28 secured on this shaft 26 and to a pulley 29 secured on the shaft 17. The crossed belt causes the belt 24 to travel in a direction opposite to that of the belt 21 and said belt is adapted to remove the filled cartons or containers.

Two bars 30 project from the end of the main frame at the top thereof and are braced at their outer ends by the rods 31. Guards 32 are secured to these bars 30 and to the main frame and they project upwardly therefrom. A shaft 33 is revolubly supported in the outer ends of the bars 30 and upon it are attached two sprockets 34 and 35. At the opposite end of the main frame

is another revoluble shaft 36 supporting two sprockets 37 and 38. The chains 39 and 40 connect the alined sprockets 34 and 37, and 35 and 38 respectively. A third shaft 41 is 5 suitably revolubly mounted on the main frame and carries the sprockets 42, upon which the chains 39 and 40 engage. Open ended pans 43 are attached to both chains 39 and 40 in suitable manner so that when the 10 chains are moved in the direction of the arrow (Fig. 2) the pans will follow the curvature of the sprocket wheels and not crowd each other. When the pans are travelling 15 in upright position the guards close the open ends of the pans and it is while the pans are between the guards that the material or commodity to be packaged is deposited therein. The shaft 36 is driven by a sprocket 44 (Fig. 1), chain 45 and sprocket 20 46 secured to the shaft 47. Two gears 48 are secured to the shaft 47 and segment gears 49, secured to a shaft 50, are adapted to mesh with the gears 48 at intervals so as to drive the commodity carrier intermittently a sufficient distance to move the pans to the selected discharging position successively. The shaft 50 is continuously driven 25 by a sprocket wheel 51 thereon, the chain 52 and the sprocket wheel 53 secured to the 30 shaft 13.

A bevel gear 54 is secured to the shaft 8 and meshes with a gear 55 secured to a shaft 56. A sprocket wheel 57 is secured to the shaft 56 and a chain 58 is engaged on this 35 wheel 57 and upon a sprocket wheel 59 secured to a shaft 60. A chain 61 engages a sprocket wheel 62 secured to the shaft 60 and it also engages a sprocket wheel 63 secured to a shaft 64. A cam 65 40 (Fig. 4) is secured to the shaft 64 and is adapted to engage a lug formed on or secured to the outer face of a flexible wall 66 suitably suspended above the belt carrier 24. This wall 66 cooperates with the fixed wall 45 67 to form a guiding chute for the filled cartons or packages in their descent upon the carrier 24, the flexible wall being intermittently flexed toward the wall 67 by the cam 65 as each carton descends in order to break 50 the fall of the package and avoid injury to the contents thereof.

Above the chute formed by the walls 66 and 67 is a tray or carrier 68 adapted to receive and support a carton. The outer side 55 and upper and lower ends of the carrier are open and at the lower end of one side thereof is a pivoted latch 111 engaged by a cam 110 (hereafter referred to) by which the latch is rocked intermittently to cause the free 60 arm thereof to project inwardly for supporting the carton that is within the carrier, the cam rocking the latch at the proper time to release the filled carton. At the forward edge of each side member of the carrier is a 65 spring plate 68^a carrying a dog 68^b. The

dogs give outwardly when a carton is pushed against them, and after the carton has passed them they prevent the carton from tilting forwardly in the carrier. This carrier is mounted upon an arm 69 that is mounted 70 on a shaft 70, (Fig. 4).

A roller 71 is mounted on the arm 69 and rides on the periphery of a cam 72 secured to the shaft 56. As the cam is rotated in the direction of the arrow (Fig. 4), the arm is caused to rock upwardly raising the carrier 68. The arm 69 is properly curved to move the carrier to a horizontal position and in horizontal alinement with the pans 43 as they successively come to rest just beyond 80 the end of the guards 32.

In order that the cartons may be successively moved off the carrier 21 into the elevating carrier 68, I provide a pusher plate 73 and secure it to a bar 74 that is longitudinally movable between two rollers 75 mounted on the frame member 76. The opposite end of the bar is pivoted to an arm 77 (Fig. 4) that is suitably pivoted at 78. A pin 79 on the arm 77 engages in the slot 85 of a cam 80 secured to a shaft 81 that is chain driven by the shaft 56.

As shown in Fig. 4, the upper end of the flexible wall 66 is extended laterally under the carrier 21. This lateral extension forms 95 a surface upon which the cartons slide successively under the influence of the pusher plate.

The contents of the pans 43 are ejected 100 into the cartons or receptacles by a plate 83 that is pivoted to one end of a link 84. The opposite end of the link is pivoted to a lever 85 that is pivoted at its lower end to a bracket 86. A link 87 is also pivoted to the lever 85 and to a crank 88 secured to a shaft 89 that is driven by a shaft 90 and gearing 91 (Fig. 5). An arm 92 is secured to the shaft 90 and is engaged in the slot of a cam 93 secured to shaft 13. This cam slot is so formed that the ejector plate 83 will be reciprocated inwardly at the proper time and then withdrawn.

Where paper board cartons are used it is necessary to turn out the flaps at the open end so that the materials may be deposited 115 into the cartons by the ejector plate 83. To accomplish this, I reciprocably mount a tapered plunger 94 upon an upwardly inclined frame 95 adjacent to the point at which an elevated carton will come to rest, the normal 120 position of the plunger being above and forwardly of the open or unclosed end of the carton as shown in Fig. 2. The downward movement of the plunger forces the end flaps of the carton outwardly and the top flap upwardly. To operate this plunger intermittently, I pivot a lever 96 to the stem 94^a of the plunger and pivot the lever to the frame 95 at 96^a. A spring 97 is connected to the lever and to the frame to oppose the down- 125 130

ward movement of the plunger. A rod 98 is reciprocably mounted on the frame 95 and is adapted to abut the lever 96 and rock it to lower the plunger. The lower end of the rod 98 carries a roller 99, Fig. 11, that rides upon a cam 100 secured to the shaft 60. The cam is properly formed to raise the rod 98 at the proper time and then release it so that the spring 97 will retract the plunger and return the rod 98.

The lower flap at the open end of the carton is pulled down by a member 101 having a lip 101^c at its upper end normally projecting into the path of the moving carton. 15 When the member is reciprocated downwardly it draws the flap with it as shown in Fig. 4. The lower end of this member 101 is suitably formed to ride on a cam 102 secured to a shaft 103 that is driven, through 20 the sprocket chain 104, by the main shaft 8.

A spur gear 105 on the shaft 103 meshes with a spur gear 106 on a shaft 107, which shaft 107 drives a shaft 108 by means of the sprocket chain 109 (Fig. 1). The cam 110 is secured to the shaft 108 and is adapted to trip the latch 111 as described above to release a filled carton, the cam 65 causing the flexible side of the chute to retard the descent of the carton and finally releasing the 30 said side so that the carton drops gently upon the carrier 24.

The cam 72 (Fig. 4) is of a proper form to raise the arm 69 and carton elevator at the proper time, hold the elevator in horizontal 35 position while the materials are deposited in the carton, then lower the elevator with the filled carton and maintain the elevator in proper position to discharge the filled carton, and to receive an empty carton.

40 An outward extension 73^a on the pusher plate 73 projects across the carrier 21 when the plate has been moved inwardly, and said extension forms a stop to hold back the empty cartons on the carrier while the plunger 45 is in operation.

The conveyer pans 43 will be formed to contain the quantity of materials that the cartons are designed to contain, so that, by filling each pan as it travels in a horizontal plane toward the ejector mechanism, the 50 contents thereof will be contained in a carton. The feed to the pans may be varied as desired in accordance with the size of the carton.

55 What I claim is:

1. In a packaging machine the combination of an intermittently driven conveyer adapted to carry the materials to be packed, a carrier adapted to be moved intermittently into the horizontal plane of the conveyer, means to convey an empty container into the carrier, means to eject the materials from the conveyer into the carried container and means to convey the filled container 60 from the carrier.

2. In a packaging machine the combination of a conveyer including a series of receptacles adapted to carry the materials to be packed; a swinging carrier, means to deliver containers in succession to the carrier when the carrier is in normal position, means to move the carrier with a container therein into opposition with one of the receptacles, means to eject the materials from said receptacle into the container and means to convey the filled container from the carrier upon the return of the carrier to normal position.

3. In a packaging machine the combination of a main frame, an intermittently driven conveyer mounted on the frame and including a series of receptacles for the materials to be packed, a pivoted carrier on the frame normally disposed below the conveyer and adapted to be swung into horizontal alignment with the receptacles and in opposition therewith, means on the frame to convey empty containers toward the carrier, means to move the containers successively into the carrier, releasable means on the carrier to support the container therein and adapted when released to permit the filled container to move by gravity from the carrier, a reciprocable member on the frame to eject the materials from one of the receptacles into a container in the elevated position thereof and means on the frame to convey the filled receptacles upon their descent from the carrier.

4. In a packaging machine the combination of a main frame, an intermittently driven endless conveyer mounted on the frame and including a series of receptacles for the materials to be packed, a carrier pivoted at one side of and below the conveyer and adapted to be swung intermittently from a vertical position to a horizontal position in opposition with the receptacles successively, means to convey empty containers toward the carrier, a reciprocable push member to move the containers into a carrier successively when the carrier is in a vertical position, means to open the mouth of the container when moved upwardly by the carrier, means to move the materials from the receptacles into the containers successively when the same are in opposition and means to convey the filled containers as released from the carrier.

5. In a packaging machine the combination of a frame, a conveyer mounted on the frame and including a series of open ended receptacles, means to drive the conveyer intermittently, fixed guards on the frame at opposite sides of the conveyer to close the open ends of the receptacles during a portion of their travel, a reciprocable ejector on the frame at one side of the conveyer and adapted to enter each receptacle after it has passed the guards and to move the mate- 120 125 130

rials therein through the opposite open end thereof, a carrier mounted on the frame for successively disposing empty containers adjacent the said opposite open ends of the 5 receptacles respectively, means to open the mouth of each container as it reaches said receptacle, means to insert the empty con-

tainers into the carrier successively, and a conveyer, the carrier being adapted to deposit the filled containers upon the latter 10 conveyer.

In witness whereof I have hereunto subscribed my name this 27th day of May, 1926.

HARVEY MULLENDORE.
